JOHN F. KYTLICA, OF CHICAGO, ILLINOIS.

VALVE MECHANISM.

1,281,030.

Specification of Letters Patent.

Patented Oct. 8, 1918.

Application filed March 13, 1918. Serial No. 222,062.

To all whom it may concern:

Be it known that I, JOHN F. KYTLICA, a citizen of the United States, residing at Chicago, county of Cook, and State of Illinois, have invented certain new and useful Improvements in Valve Mechanism, of which the following is a specification.

This invention relates to improvements in valve mechanism or construction, and particularly to such mechanism designed for use on internal combustion engines of the "T-head motor" type, although it is applicable for use in connection with other types of engines and for other uses, and for this reason I wish it understood that I do not limit myself in its use or application, but may employ it wherever it may be found practicable.

The invention consists in certain peculiarities of the construction, novel arrangement and operation of the various parts thereof as will be hereinafter more fully set forth and specifically claimed.

In the type of engines or motors above mentioned, as heretofore constructed, lift or puppet valves operated by the pressure of the gases or of the atmosphere, or by suitable cam mechanism and springs have generally been employed, and experience shows that such valves are open to many objections, among them, the uncertainty of operation attendant upon springs or other non-positive returning means, and the noise produced by the operation of the parts.

One of the objects of the invention is to provide means for controlling the admission and exhaust of the motive agent or fluid and the burned gases or inert fluid, respectively, which shall obviate the objections above referred to, and which shall be simple and inexpensive in construction, strong, durable, and efficient in operation. Another object of the invention is to provide valve mechanism of such construction that it can be used instead of the commonly employed puppet valves without material change in the engine head construction. Still another object is to provide a self-lubricating valve mechanism provided with means to cause the valve casing to wear evenly and to expand as the casing becomes worn, thus preventing leakage. A further and very important object is

to provide reciprocating or sliding piston valves with means for their positive, uniform, and noiseless operation, and so that very high speed of the engine may be obtained with the certainty that the charges of the motive agent into the compression chamber and a thorough direct exhaust of the exploded products from said chamber will occur regularly at intermittent intervals. 65 Other objects and advantages of the invention will be disclosed in the subjoined description and explanation.

In the accompanying drawings which serve to illustrate an embodiment of the invention—

Figure 1, is a vertical sectional view showing a portion of one end of an internal combustion engine of the "T-head" motor type with my improved valve mechanism located 70 in one of the valve casings thereof, said view being taken on line 1, 1, of Fig. 2.

Fig. 2, is a plan view partly in section and partly in elevation taken on line 2, 2, of Fig. 1.

Fig. 3, is a detached perspective view of the detachable barrel or cylinder of the mechanism, and

Fig. 4, is a similar view of the washer used for holding certain packing rings in 80 position.

Corresponding numerals of reference refer to like parts throughout the different views of the drawings.

The reference numeral 5, designates a portion of the engine cylinder which may be provided with a water jacket 6, and spark plug 7, of the ordinary or any well known construction and arranged or located in the usual manner. In the present instance, a 90 part of an engine of the "T-head" type is shown with one valve mechanism only therefor as the other would be a duplicate and consequently it is unnecessary to show and describe it. For the sake of explanation 95 and description, it will be assumed that the valve mechanism shown in the drawings is for the control of the inlet of motive fluid, but it will be understood that the valve for the control of the exhaust of the engine is 100 of the same construction and operation. In an internally screw threaded bore or open-

ing 8, in the lateral extension 9, of the head of the engine is located an externally screw threaded barrel or cylinder 10, which has near its inner end a plurality of ports 11, 5 which extend circumferentially with respect to the said barrel or cylinder and communicate, one or more of them directly with the compression chamber 12 of the engine, while the others communicate with a circumferential groove or enlargement 13, on the inner surface of the lateral extension 9, of the cylinder head. This circumferential groove 13, communicates with the compression chamber 12, as is clearly shown and will be 10 readily understood by reference to Fig. 2, of the drawings. As will be seen by reference to Fig. 1, of the drawings, the extension or valve casing 9, is provided in its portion opposite the open end of the bore or opening 15 therein with a port 14, which in the present instance is the inlet port of the engine. Inwardly of the port 14, the casing or extension 9, is provided with an annular valve seat 15, the face or wall of which is inwardly and downwardly tapered as is usual 20 in the construction of valve casings where puppet valves are employed. In fact, the valve casing or extension 9, in its self is of the ordinary engine construction employed 25 in "T-head" engines but the cage and puppet valve usually employed are omitted or dispensed with and my improved barrel or cylinder 10, is used instead of said cage and a centrally apertured plug or block 16, having 30 its surface adjacent to the valve seat 15, shaped to correspond with said seat is employed in lieu of the puppet valve but for a different purpose.

This block or member 16, is circular in 35 shape and hollow in its lower portion and is mounted on or made integrally with a sleeve 17, which sleeve is centrally located in the barrel or cylinder 10, and extends through a suitable opening in the casing or extension 40 9, at one end thereof. Each end of the sleeve 17, is externally screw threaded to engage nuts 18, 19 and 20, used for rigidly securing the sleeve in position within the barrel and casing and for regulating the 45 tension of a spring 21 which surrounds said sleeve near one of its ends and is used to actuate a circular washer 22, which is loosely mounted on the sleeve and is employed for the purpose to be presently explained. As 50 shown in Figs. 1 and 2, of the drawings, the block or member 16 is united to the sleeve by means of radial arms 23, and is of sufficient size at its portion adjacent to the valve seat 15, to fit closely in the barrel or cylinder 55 10, so as to prevent leakage. As a further means for preventing leakage an annular gasket 24, of leather or other suitable material may be interposed between the valve seat 15, and the surface of the block 16, ad-

jacent thereto. The upper portion of the 65 block 16, or that portion thereof opposite the seat 15, is provided with a transverse floor 25, which closes the cavity of said block or member and said floor or partition is provided on its outer surface with an annular 70 extension 26, terminating at its free edge in an outwardly extended flange 27, which is of less diameter than the cavity of the cylinder 10, or barrel. This construction of the upper portion of the block 16, or that 75 portion thereof opposite the seat 15, provides an annular recess 28, in the outer surface of the partition 25, in which recess the inner portion of the washer 22, is movably located. As shown in Fig. 1, of the drawings 80 the washer 22, has a recess 29, in its central outer portion and is provided at its periphery with an annular flange 30, surrounding the flange 27, of the partition 25, of the block 16, but in loose engagement 85 therewith. The spring 21, is located in the recess 29, and rests at one of its ends against the washer 22 and at its other end against the nut 19, by means of which nut the tension of said spring can be regulated so as to 90 afford the desired pressure to the washer. The block or member 16, is provided with an annular channel or recess 31, which extends from the flange 27, thereof to a point near 95 that part of said block or member which contacts with the barrel 10, as at 32, near the seat 15, of the extension 9, or valve casing. Located in the channel 31, one on the other are packing rings 33 and 34, which are transversely split or broken at diametrically 100 opposite points to permit of expansion and contraction. The packing rings 33, or the outer one is provided at its edge adjacent to the flange 30, with a shoulder 35, against which said flange will rest so as to press 105 said ring against the opposite wall of the channel 31, in which said rings are located. It will be observed by reference to Fig. 1, of the drawings that the portion of the ring 33, adjacent to said flange is reduced as at 110 36, and that a circular space 37, between said ring and the barrel 10, is provided in which the piston valve 38, is adapted to operate. This valve is cylindrical in shape and is provided on its periphery with a number of annular grooves 39, for the distribution of a suitable lubricant and is mounted on one 115 end of the operating rod 40, which extends through the sleeve 17, and may be reciprocated in any suitable manner, but in the present instance I have shown it as being adjustably connected by means of a screw plug 41, to the stem 42, of a yoke 43, the prongs 44, of which stride a disk 45, mounted on the cam shaft 46, of the engine. Each of the 120 prongs 44, of the yoke has an inwardly extended shaft 47, each provided with a roller 48, which shafts and rollers are adapted to

travel in cam grooves 49, on opposite faces of the cam disk. The screw plug 41, engages the threads of a recess 50, in one end of the stem 42, and said plug has in its outer end a screw threaded recess 51, which is reduced at its inner end as at 52 which construction forms an annular shoulder 53, on which will rest the members of a split washer 54, which fits around the reduced portion 55, of the operating rod 40, which rod has on its end extended into the recess 51, a head 56, on which the members of the washer 54 will also rest. Surrounding the rod 40, is a collar 57, which is screwed into the recess 51, and may be locked in the desired position by means of a lock nut 58, mounted on said collar. By this coupling arrangement it is apparent that the rod 40, will be swiveled in the plug 41, and that said plug can be suitably adjusted with respect to the stem 42, by turning it in the proper direction, and that it may be locked in the desired position by means of a lock nut 59, mounted on the plug 41. The outer surface 25 of the barrel or cylinder 10, is screw threaded to engage the threads of the extension or casing 9, and also to engage a cap 60, used for closing said barrel or cylinder, which latter is provided in its outer end with a circumferential groove 61, which communicates with a groove or channel 62, extended longitudinally in the wall of the barrel. The channel 62, communicates at its inner end with an annular groove 63, on the inner 35 surface of the barrel 10, near the ports 11, therein. The cap 60, is provided with an opening 64, with which a pipe 65, leading from a lubricating supply communicates, which pipe may be coupled to the cap 60, by means of a suitable coupling 66. By this arrangement it is apparent that oil can be supplied to the groove 61, in the barrel 10, and that it will pass from said groove through the channel 62, into the groove or 45 channel 63, from which it will be distributed on the walls of the piston valve and barrel through the medium of the channels 39, in said valve. The end of the piston valve 38, adjacent to the cap 60, is provided with openings 67, to prevent vacuum in the valve chamber. The valve 38, is provided near its end adjacent to the cap 60, with an annular groove 68, in which are located interlocking packing rings 69 and 70, to prevent leakage. 50 The packing rings 33 and 34, are provided with ports 33^a and 34^a, respectively, to register with the ports 11 in the barrel 10, and with the ports 16^a, in the block 16 as will be clearly seen and understood by reference to Fig. 2 of the drawings.

Having thus fully described my invention, what I claim as new and desire to secure by Letters Patent is—

1. The combination with a valve casing

having a port and an opening in one of its ends, of a sleeve located in said opening and extended into the casing, a barrel mounted in the casing and having a port in communication with the port of the casing, a block mounted on said sleeve and seated within the casing at the inner end of the barrel, said block having a central cavity in communication with the said ports, a piston like valve slidably mounted between said block and barrel, an operating rod connected at one of its ends to said valve and extended through said sleeve, and means operatively connected to the other end of said rod for reciprocating it and the valve.

2. The combination with a valve casing having a port and an opening in one of its ends and provided with a circumferential enlargement of its cavity between its ends, of a sleeve located in said opening and extended into the casing, a barrel mounted in the casing and having a plurality of ports in communication with the port of the casing and with the said enlargement, a block mounted on said sleeve and seated within the casing at the inner end of the barrel, said block having a central cavity in communication with said ports, a piston like valve slidably mounted between said block and barrel, an operating rod connected at one of its ends to said valve and extended through said sleeve, and means operatively connected to the other end of said rod for reciprocating it and the valve.

3. The combination with a valve casing having a port and an opening in one of its ends, of a sleeve located in said opening and extended into the casing, a barrel detachably mounted in the casing and having at least one port in communication with the port of the casing and with the engine cylinder, a block mounted on said sleeve and seated within the casing at the inner end of the barrel, said block having a central cavity in communication with the port of the casing and provided in its walls with ports communicating with the port of the barrel, a piston like valve slidably mounted between said block and barrel, an operating rod connected at one of its ends to said valve and extended through said sleeve, and means operatively connected to the other end of said rod for reciprocating it and the valve.

4. The combination with a valve casing having a port, and an opening in one of its ends, of a sleeve located in said opening and extended into the casing, a barrel detachably mounted in the casing and having at least one port in communication with the port of the casing and with the engine cylinder and provided with a channel adapted for communication at one of its ends with a supply of lubricant and having an outlet for said lubricant, a block mounted on said sleeve

- 4
- and seated within the casing at the inner end of the barrel, said block having a central cavity in communication with the port of the casing and provided in its walls with at least one port communicating with the port of the barrel, a piston like valve slidably mounted between said block and barrel, an operating rod connected at one of its ends through said valve and extended through said sleeve, and means operatively connected to the other end of said rod for reciprocating it and the valve. 5
5. The combination with a valve casing having a port and an opening in one of its ends and provided with a circumferential enlargement of its cavity between its ends, of a sleeve located in said opening and extended into the casing, a barrel mounted in the casing and having a plurality of ports in communication with the port of the casing and with said enlargement, said barrel having a channel extended from its outer end inwardly and provided with an outlet inwardly therefrom, said barrel also having a circumferential groove in its outer end communicating with said channel, a block mounted on said sleeve and seated within the casing at the inner end of the barrel, said block having a central cavity in communication with said ports, a piston like valve slidably mounted between said block and barrel, an operating rod connected at one of its ends to said valve and extended through said sleeve, and means operatively connected to the other end of said rod for reciprocating it and the valve. 10
6. The combination with a valve casing having a port and an opening in one of its ends, of a sleeve located in said opening and extended into the casing, a barrel mounted in the casing and extended therefrom at one of its ends and having a port in communication with the port of the casing, a block mounted on said sleeve and seated within the casing at the inner end of the barrel, said block having a central cavity in communication with said ports, a cap engaging the outwardly extended portion of said barrel, a piston like valve slidably mounted between said block and barrel, an operating rod connected at one of its ends to said valve and extended through said sleeve, and means operatively connected to the other end of said rod for reciprocating it and the valve. 15
5. The combination with a valve casing having a port and an opening at one of its ends, of a sleeve located in said opening and extended into the casing, a barrel mounted in the casing and having a port in communication with the port of the casing and with the engine cylinder, a block mounted on said sleeve and seated within the casing at the inner end of the barrel, said block having a central cavity in communication with said ports and provided on its periphery with an annular recess, a plurality of packing rings surrounding said block and located in said recess, a piston like valve slidably mounted between said block and barrel, an operating rod connected at one of its ends to said valve and extended through said sleeve, and means to reciprocate said rod and the valve thereon. 20
8. The combination with a valve casing having a port and an opening at one of its ends, of a sleeve located in said opening and extended into the casing, a barrel mounted in the casing and having a port in communication with the port of the casing and with the engine cylinder, a block mounted on said sleeve and seated within the casing at the inner end of the barrel, said block having a central cavity in communication with said ports and provided on its periphery with an annular recess, a plurality of packing rings surrounding said block and located in said recess, a spring actuated washer surrounding said sleeve and having at its periphery a flange to contact with one of said rings, a piston like valve slidably mounted between said block and barrel, an operating rod connected at one of its ends to said valve and extended through said sleeve, and means to reciprocate said rod and the valve thereon. 25
9. The combination with a valve casing having a port and an opening in one of its ends and provided with a circumferential enlargement of its cavity between its ends, of a sleeve located in said opening and extended into the casing, a barrel mounted in the casing and having a plurality of ports in communication with the port of the casing and with the said enlargement, a block mounted on said sleeve and seated within the casing at the inner end of the barrel and having an annular recess in its periphery, said block having a central cavity in communication with said ports, a plurality of broken packing rings surrounding said block and located in said recess thereof, a spring pressed washer surrounding said sleeve and having at its periphery a flange resting against one of said rings, a valve slidably mounted and extended between said springs and barrel, an operating rod connected at one of its ends to said valve and extended through said sleeve, and means to reciprocate said rod and the valve thereon. 30
10. The combination with a valve casing having a port and an opening in one of its ends, of a sleeve located in said opening and extended into the casing, a barrel mounted in the casing and having a port in communication with the port of the casing, a block mounted on said sleeve and seated within the casing at the inner end of the barrel, having a central cavity in communication with said ports and provided on its periphery with an annular recess, a plurality of packing rings surrounding said block and located in said recess, a piston like valve slidably mounted between said block and barrel, an operating rod connected at one of its ends to said valve and extended through said sleeve, and means to reciprocate said rod and the valve thereon. 35
- 60

said block having a central cavity in communication with said ports, a piston like valve slidably mounted between said block and barrel, an operating rod connected at one 5 of its ends to said valve and extended through said sleeve, a cam shaft journaled near the other end of said rod, a disk on said shaft having a cam groove therein, a con-

necting member having a stub shaft extended into said cam groove, and a coupling 10 adjustably uniting said member to the operating rod.
